UNITED STATES PATENT OFFICE

JOSEF MEISER, OF DORTMUND, GERMANY

ROLLING OF CHANNEL SECTIONS WITH WIDE FLANGES

Application filed January 13, 1930, Serial No. 420,577, and in Germany February 25, 1929.

My invention relates to method of rolling channel sections, especially those with wide flanges and aims to provide a desirable improvement.

5 In rolling metal sections by the operation of conducting metal bars through "passes" comprising pairs of rolls that gradually approximate the form and shape of the finished section, it is necessary for the centre of gravity of the cross sectional surface of each section (corresponding to the "pass" for the time being) to lie nearly as possible in a line drawn midway between the axes of the two rolls and parallel therewith.

15 When dealing with wide-flange channel sections wherein the centre of gravity is situated very near the web of the iron, the fulfillment of the above condition of the rolling art (as is essential for steady running) has 20 heretofore made it necessary to very considerably weaken the roll that acts on the hollow side of the channel, at the part occupied by the flanges. Consequently, either a rapid destruction of the rolls had to be counted upon, 25 or stronger and heavier rolls had to be used.

My invention obviates this disadvantage or necessity for stronger and heavier rolls which are costly, in that, while maintaining the total width of the section always the same, I cause 30 the web of the roughed section, between the flanges, to draw towards the interior of the channel, thus displacing the centre of gravity of the cross section away from the web and in the direction of the flanges, the web being flat- 35 tened out only in the final finishing pass. At that stage, however, the weakening of the rolls is not so important, the final pass being situated near the bearings of the rolls.

40 A practicable embodiment of the invention is diagrammatically illustrated in the accompanying drawings, in which:—

Fig. 1 shows a first pair of roughing rolls in side elevation;

45 Fig. 2 is a similar elevation of a second pair of roughing rolls;

Fig. 3 shows the pair of finishing rolls; and

50 Fig. 4 shows how the displacement of the centre of gravity is effected by modifying

the shape of the roughed sections according to my invention.

It is assumed in the representation that a rolled bar must be put through ten passes denoted at 1, 2, 3 et seq. to 10. In the first 55 pass, 1, it is given the cross sectional form A, and thereafter in succession the forms B, C, D by the first pair of rolls R_1 and R_2 ; then it is given in succession the forms E, F, G by the second pair of rolls R_3 and R_4 ; and lastly 60 it is given in succession the forms H, J, K between the final pair of rolls R_5 and R_6 .

In each of Figs. 1 to 3, the central axes of said pairs of rolls (R_1 and R_2 ; R_3 and R_4 and R_5 and R_6) are indicated by the dot-and-dash 65 lines $a-a:a-a$, while the line of action, midway between said axes and crossed at equal speed by corresponding points of the co-acting pair of rolls, is indicated by $b-b$. As already stated, it is necessary in rolling- 70 mill practice to have the centre of gravity of the cross sectional surface of each of the several forms A, B, C et seq. to K coincide approximately with this line $b-b$, so that, in 75 rolling, the axes of gravity will be situated in the plane of mean velocity between the two rolls.

To attain the specified object in shaping a 80 rolled section of the cross-sectional form K, without having to weaken the rolls unduly in places, I give the roughed sections, forms that progressively approach the shape of the letter M, so that the web of the channel section will be depressed or recessed in the centre like a saddle, this shape being re- 85 tained up to the last roughed section J, shown at the pass 9 in Fig. 3.

Fig. 4 shows what transverse displacement and what saving in the diameter of the rolls I effect in this manner. The heavy outline, 90 obliquely hatched, illustrates the course of the web of a roughed section approximately corresponding to the form J in the pass 9, whilst the adjacent thinner outline shows the penultimate shape obtained in existing 95 rolling-mill practice. It will be seen that this shape is substantially straight at c. The axis of gravity of this usual shape is indicated by the line $a-a$. Now, as the result of my giving the web the curved form repre- 100

sented by $d e f$ and, at the same time, drawing the flanges of the section slightly in towards the centre, as shown, the axis of gravity is displaced from the position $x-x$ to $y-y$ and the centre of gravity is displaced, by 5 the distance z , from the point S_0 to the point S in the direction of the free ends of the flanges. It will be apparent that to maintain the aforesaid condition while employing the usual shapes of roughed sections with 10 straight web c , the roll R_5 would have to be cut deeper, by said distance z , in the centre in pass 9, and would therefore be considerably more liable to damage in rolling.

By not pressing the web out flat until 15 the final pass 10, it is unnecessary to recess the roll R_5 more deeply except in this particular portion which is near the bearing of the roll. Consequently, the roll is subjected to less stressing as a whole, and has a lesser 20 tendency to fracture.

Having now particularly described and ascertained the nature of my said invention and in what manner the same is to be performed, I declare that what I claim is:—

25 1. In a method of producing channel sections of metal with wide flanges by passing a blank or bar of the metal through a succession of forming spaces or passes between oppositely rotated pressure rolls, the improvement which consists in drawing the intermediate or web portion of the forming section inward toward the center of the channel in the successive stages while maintaining the width thereof always the same, so that the 30 centre of gravity of the section will be displaced in the direction of the free ends of its flange portions, and in the final step or pass back-drawing and flattening said web portion while still maintaining the section at the 35 same width.

40 2. In the process of producing channel sections of metal with wide marginal flanges by passing a blank or bar of the metal through a plurality of successive forming spaces or "passes" between oppositely rotated press rolls, the improvement which consists in drawing the central portion of the formative blank in the successive stages of 45 formation inwardly toward the center in the mean direction of its sides simultaneously shaping into the flange portions of the finished section without varying the width of the piece from that originally, so as to displace the centre of gravity of the forming section in said direction or toward the free 50 ends of its flange portions during the successive press actions, and finally back-drawing and flattening out said central portion 55 forming the web of the section while maintaining it still at the original width.

60 3. The improved method of producing channel sections of metal with wide marginal flanges, characterized by passing a blank or 65 bar of the metal through a progressive suc-

cession of forming spaces or "passes" between oppositely rotated rolls pressing the same into shape; drawing the central or web-forming portion of the gradually shaped section inwardly toward the center in the mean direction of its simultaneously forming flange portions without varying the width of the section from that of the original blank, so as in the successive stages to displace the section's center of gravity in said direction 70 toward its free ends; and in the final step or pass drawing said central web-forming portion in oposite direction to a flat plane with flange portions at desired angle there-to in the completely formed section, while 75 maintaining the latter still at the same width.

4. A method of rolling channel sections of metal having webs and wide flanges which consists in passing the blank through roughing passes and then through a finishing pass 85 between shaping rolls, maintaining in all said roughing passes the metal to a constant width and simultaneously in said roughing passes drawing said web of the roughed channel sections inwardly between the flanges toward their free ends so as to displace the center of gravity of the sections and then, in the said finishing pass, flattening said web portion while still maintaining the section at said constant width.

In testimony whereof I affix my signature.
JOSEF MEISER.
